STAGE LIFT PUMP

Walter G. Hurley, Gladewater, Tex., assignor of
one-third to Horace Hamilton, Wharton, Tex.

Application May 17, 1945, Serial No. 594,203

3 Claims. (Cl. 103—248)

1

This invention relates to apparatus for elevating fluids from wells and more particularly to stage lift pumps.

The principal object of the invention is to provide a fluid displacement unit adapted to be suspended with other identical units in a producing well for submergence in the fluid therein. Through the provision of a float actuated valve, a gaseous pressure medium maintained in the well casing exteriorly of the unit at a predetermined pressure is introduced into the latter to displace fluid upwardly into preceding units to the surface, the said valve being also effective upon recession of the float to evacuate the unit of gas through an exhaust pipe coextensive with the tubing and unit assembly.

Another object of the invention is to provide a simplified fluid lift in which the float controlling the ingress and egress of the pressure medium is semi-cylindrical and operates in a correspondingly shaped casing or guide in the housing of the apparatus but is substantially less in length than said guide. The guide is capable of limited longitudinal displacement under thrust of the buoyed float to open a valve to ingress of a pressure medium and falls under its own weight to change the valve position subsequent to evacuation of fluid from the housing by said pressure medium, to release the latter to exhaust preparatory to a renewed cycle of operation.

With the foregoing objects as paramount, the invention has further reference to certain features of accomplishment which will become apparent as the description proceeds, taken in connection with the accompanying drawings wherein:

Figure 1 is an elevational view of one unit constructed according to the invention, in vertical section, shown in a well casing.

Figure 2 is a similar but enlarged view of the upper portion of the unit.

Figure 3 is a view in transverse section taken on line 3—3 on Figure 1.

Figure 4 is a view in transverse section taken on line 4—4 on Figure 2, and

Figure 5 is a perspective view of a form of pressure control valve, partly broken away.

Continuing with a more detailed description of the drawing, reference numeral 10 denotes the casing of a producing well. The depth of the well

determines the number of fluid displacement units to be employed and it has been found to be practicable to suspend these units about 500 feet apart on the tubing string 11 so that at least the lowermost of the units will be submerged in the fluid of the well.

All of the lifting or displacement units are identical in construction and each consists of a swaged nipple 12, connected by means of a collar 13 to each end of a pipe section 14 of a predetermined length and this assembly will be herein-after referred to as the unit housing.

Within the unit housing is arranged a fluid displacement tube 15, the upper end of which has a double curve or offset so that it may be concentric with the suspending tubing 11 and in order that the body thereof will extend flush against the wall of the housing 14 to a point near the bottom of the latter, as shown in Figure 1. In the lower end of the displacement tube 15 there is provided a check valve 16 of any suitable design and below this valve, in the nipple 12, is a standing valve 17 of similar design and function.

It is apparent from the foregoing that well fluid rising through the tubing 11 below the housing 14 will enter the latter and will be constrained by the valve 17 to pass upwardly into the displacement pipe 15, past valve 16. When a gaseous medium at sufficient pressure is introduced into the unit housing and in being so displaced, the fluid will enter the next adjacent unit above, to be similarly displaced to the surface.

The gaseous medium employed to operate the units is introduced from the surface under pump pressure into the space 18 between the unit and casing 10. The pressure is maintained constant at approximately 175 pounds since it has been determined that a column of fluid can be elevated a distance of approximately 500 feet at this pressure. Hence the units are spaced apart in the well a distance slightly under 500 feet.

Near the upper end of each unit there is provided an inlet port 19 for the gaseous pressure medium, which port is in control of a valve, generally indicated by reference numeral 20 and shown in detail in Figure 5.

This valve is of the two-way variety and while a specific construction is shown in Figure 5, no limitation is intended since variation in design may be required under different circumstances.

The valve 20, as shown, consists of the body bearing the same reference numeral and which is longitudinally bored at 21 to accommodate the pressure medium entering the housing from the casing when the core 22 of the valve is opened. The core 22 is preferably tapered, although not so shown, to maintain proper seal and to compensate for high pressures, an anti-friction thrust bearing 23 is provided thereon.

Communicating with the axial bore 21 in the valve body 20 is a vertical bore 24 which, in turn, communicates with a pipe 25.

The pipe 25 enters a vertical exhaust pipe 26, which extends alongside the tubing 11 and enters the upper end of each unit housing 14 to pass through the same to the bottom of the entire unit assembly. This pipe discharges to atmosphere at the surface.

It is apparent from the foregoing that in one position of the valve core 22, pressure will enter the unit housing 14 through port 19 and will be expelled therefrom through the exhaust pipe 26 when the core 22 is moved to the other of its two positions.

To actuate the valve 20 as described, a float chamber 27 is provided, which as apparent in Figures 3 and 4 is semi-circular in transverse section, to conform to one side of housing 14 in which it depends to a point spaced from the bottom of the unit. This chamber is permitted to move vertically a limited distance as indicated by broken lines in Figures 1 and 2. Within the chamber 27 is a buoyant element or more specifically a float 28, preferably made of a wooden core covered by a metallic sheathing 29 (Fig. 4). The float is substantially half the length of the chamber 27 in which it reciprocates in order to increase the quantity of fluid displaced.

Near the upper end of the chamber 27 is a pair of cross bars 30 against which the float 28 bears when it is elevated by fluid rising in housing 14. Upon engaging the bars 30, continued upward movement of the float will raise the float chamber 27, aided by the counterbalancing spring 31, connected at one end to the chamber and at its upper end to the bend of fluid pipe 15.

Pivoted to a transverse rod 32 at the top of the chamber 27 is an arm 33. This arm extends upwardly at an angle and is pivoted at α to a second valve actuating arm 34. The valve actuating arm is affixed to the core 22 of valve 20 and the relationship of the arms 33 and 34 and the degree of displacement of chamber 14 are calculated to move the valve core 90° or to impart thereto sufficient movement to align the passage 35 therein with respective passages or bores 21 and 24 in the valve body 20.

In order to maintain operative relationship of the valve actuating arms 33 and 34, a spring 36 is connected at one end to a point on arm 34 near pivot point α and at its opposite end to the wall of the housing 14. A stop 37 on arm 34 (Fig. 1) limits relative displacement of arms 33 and 34 in both raised and lowered positions.

In order to maintain perpendicularity of the float chamber 27, guide rods 38 are disposed in parallel relation to the sides of the chamber and are secured at their upper and lower ends to the walls of the housing 14. Arms 39, secured to the flat side of the chamber 27 slidably embrace rods 38 to hold the float chamber in properly spaced relation to the walls of the housing 14 to prevent frictional resistance to its vertical movement.

In operation, well fluid, seeking its level or under pressure of the gaseous medium in the

casing 10 will rise in the housing 14 through standing valve 17. As it rises in the housing 14, the fluid will raise the float 28 until the latter engages the cross bars 30, whereupon the float chamber 27 will begin to move upwardly. This action causes movement of the arms 33 and 34 to a point where the spring 36 will cause sudden movement of the core 22 of the valve to a position to admit the pressure medium exteriorly of the housing 14 into the latter through port 19 and valve passage 21. Pressure thus introduced will impose a pressure head on the column of fluid in housing 14 sufficient to force the fluid upwardly into pipe 15 past the valve 16 and into the tubing 11 to be ultimately received and similarly acted upon by other units above.

It will be observed in Figure 1 that the lowest position of float 28, which recedes under its own dead weight as well as the pressure imposed thereon from above, is sufficiently above the bottom of housing 14 to provide a liquid seal about the lower end of fluid pipe 15 to prevent ingress of gas or air. This feature not only preserves the pressure medium for active service but also saves gas and prevents a turbulent condition in the fluid displacement pipe 15.

Manifestly, the construction as shown and described is capable of some modification and such modification as may be construed to fall within the scope and meaning of the appended claims is also considered to be within the spirit and intent of the invention.

What is claimed is:

1. A stage lift apparatus for a well including a fluid displacement unit comprised of an elongated housing having a pressure inlet port adjacent its top and into which fluid rises from said well, a fluid pipe entering said housing at its top and depending to a point therein adjacent its bottom, a valve in the lower end of said pipe, a two-way rotary valve in control of said pressure inlet port, a float chamber in said housing capable of limited longitudinal movement therein, a float stop in the upper end of said chamber, a float in said chamber, a pressure exhaust pipe extending through said housing and having communication with said inlet port, a pair of relatively pivoted arms connecting the top of said chamber with said inlet valve for opening the same to pressure entering said inlet port when fluid rising in said housing elevates said float against said float stop to evacuate said fluid through said fluid pipe, and spring means in control of said arms to render them effective upon recession of said float and chamber to open said valve to said exhaust pipe.

2. A stage lift apparatus for wells including a fluid displacement unit comprising an elongated housing suspended by a tubing, having an inlet port at its top for a gaseous pressure medium and a check valve in its bottom, a two-way inlet valve in control of said port, a float actuated float chamber for operating said valve, relatively pivoted arms connecting said latter valve and said float chamber, a pressure exhaust pipe extending through said housing with which said valve communicates, a fluid pipe entering said housing at its top and terminating adjacent its bottom, a check valve in said pipe, a float in said float chamber rendered buoyant by fluid rising in said housing for displacing said float chamber to actuate said inlet valve to admit said gaseous pressure medium into said housing to displace fluid therein upwardly through said fluid pipe, means for opening said inlet valve to said exhaust pipe upon recession of said float to release

said gaseous medium from said housing and spring means for urging said pivoted arms to extreme displaced positions in the raising and lowering movements of said float chamber.

3. A fluid lifting apparatus for wells including a fluid displacement unit adapted to operate in a well, having an inlet at its top for admitting a gaseous medium under pressure, a valve in the bottom of said housing, a valve in control of said inlet, a float actuated float chamber for operating said inlet valve, a pair of spring controlled and relatively pivoted arms operatively connecting said inlet valve and float chamber, an exhaust pipe for said unit and having communication with said inlet valve, a fluid displacement pipe, a float in said float chamber rendered buoyant by well fluid rising in said unit to raise said float chamber to open said inlet valve to admit

said pressure medium to displace fluid into said displacement pipe and effective upon evacuation of said fluid to yield to the unsupported weight of said float chamber to open said valve to said exhaust pipe.
